[57] **CLAIM**

The ornamental design for a unitized power outlet housing for a truck body, as shown.

DESCRIPTION

FIG. 1 is a front elevational view of the unitized power outlet housing for a truck body showing my new design;

FIG. 2 is a right side elevational view of the unitized power outlet housing of FIG. 1 on a reduced scale;

FIG. 3 is a left side elevational view of the unitized power outlet housing of FIG. 1 on a reduced scale;

FIG. 4 is a top plan view of the unitized power outlet housing of FIG. 1 on a reduced scale;

FIG. 5 is a bottom plan view of the unitized power outlet housing of FIG. 1 on a reduced scale; and

FIG. 6 is a rear elevational view of the unitized power outlet housing of FIG. 1 on a reduced scale.
